NAIL CLAM

Roy R. Bixler, Westminster, Md.

Application September 1, 1953, Serial No. 377,848

3 Claims. (Cl. 294—117)

This invention relates to devices, such as tongs, clam shell buckets, and the like, for picking up a plurality of comparatively small objects, and in particular a hand actuated tool having a plurality of pointed fingers or prongs extended downwardly from pivotally mounted frame members whereby with the device in an open position, such as with the prongs in spaced relation, it may be inserted in a keg of nails and, by drawing upwardly on a sliding bar, the prongs may be drawn together to pick up nails from the keg whereby a comparatively large number of nails may be picked up and placed on a tray of scales or in a container without touching the nails by hand.

The purpose of this invention is to provide a grab or mechanical hand for picking up nails and the like without contacting the nails by hand.

Various types of prongs have been provided for removing nails from kegs and other containers, however, it is difficult to form such devices so that a comparatively large number of nails may be taken with each operation and the process of moving nails from one bin or container to another or from a bin or keg to a tray of scales is comparatively tedious. With this thought in mind this invention contemplates a device for picking up objects, such as nails, which actuates in the form of a clam whereby the jaws or prongs are adapted to close with a firm grip, positively holding nails as the prongs or jaws are elevated and held over a container or tray of a pair of scales.

The object of this invention is, therefore, to provide means for forming a pick-up device whereby gripping elements are adapted to be forced downwardly into a mass of objects, such as a keg of nails and wherein the gripping prongs are adapted to be brought together to retain a plurality of the nails therein.

Another object of the invention is to provide a mechanical grab device for picking up a plurality of nails and the like in which the device is resiliently actuated to free or drop the nails when it is released.

A further object of the invention is to provide a mechanical clam having spaced nail holding prongs extended from a handle in which the device is of a simple and economical construction.

With these and other objects and advantages in view the invention embodies a substantially U-shaped handle having inverted T-formations on the lower ends of arms with frames having prongs extended downwardly therefrom pivotally mounted in the ends of cross bars of said T-formations and with the prong holding frames adapted to be actuated with a slidably mounted bar to which the frames are connected with levers and links, for gripping nails and the like and in which the frames of the prongs are actuated to positions for freeing or releasing the nails upon the release of the sliding bar, by springs.

Other features and advantages of the invention will appear from the following description taken in connection with the drawing, wherein:

2

Figure 1 is a side elevational view illustrating the improved nail gripping tool, part of one end of the frame of the tool being broken away to show the slidable mounting of a bar therein.

5 Figure 2 is an end elevational view of the tool shown in Fig. 1.

Figure 3 is a cross section through the tool being taken on line 3—3 of Fig. 1.

10 Figure 4 is a plan view of the tool with the upper part of the handle broken away to show the structure of the prong holding frame.

Figure 5 is a detail showing parts of the frames with parts broken away and with one of the prong holding frames separated from the mounting frame or handle.

15 Referring now to the drawing wherein like reference characters denote corresponding parts the improved nail gripping tool of this invention includes an inverted U-shaped handle 10 having arms 11 and 12 with cross bars 13 and 14, respectively, on the lower ends of the arms and with frames 15 and 16 from which prongs 17 and 18, respectively, depend, pivotally mounted in the bars 13 and 14 and connected to a sliding bar 19 with links 20 and 21, the link 20 being connected to an arm 22 extended from the bar or frame 16 and the link 21 being pivotally 25 connected to an arm 23 extended from the bar or frame 15.

The lower ends of the prongs 17 and 18 are provided with points 24 and 25, respectively and the upper ends of the prongs 17 are secured in openings 26, in the bar 30 16. The prongs 18 are secured in similar openings, as indicated by the numeral 27, in the bar 15.

The ends of the bar 15 are pivotally mounted with pins 28 and 29 in openings 30 in the ends of the cross bars 13 and 14 and the bar 16 is pivotally mounted with 35 similar pins, as indicated by the numerals 31 and 32 in openings 33 of the cross bar.

The arm 22, which extends from the bar 16, is pivotally mounted by a pin 34 in the lower end of the link 20 and the arm 23, which extends inwardly from the 40 bar 15 is pivotally mounted by a shoulder screw 35 in the lower end of a link 21.

The upper ends of the links 20 and 21 are pivotally mounted on the sliding bar 19 and the ends of the bar 19 are positioned in vertically disposed slots 36 and 37 in the inner surfaces of the arms 11 and 12, respectively.

45 The bar 16 is connected by a spring 42 to the sliding bar 19 and the bar 15 is connected by a similar spring, also as indicated by the numeral 42 to the opposite end of the bar 19.

A plate 43 is secured to the under surfaces of the 50 cross bars 13 and 14, providing a closure for the intermediate part of the tool and also providing means for protecting the fingers of a hand on the handle 10 from nails or other sharp devices being picked up by the prongs.

With the parts formed and assembled in this manner 55 the tool is gripped by the handle 10 and with the prongs in the free positions, as illustrated in Fig. 2 they are forced downwardly into a mass of nails, such as nails in a keg or bin and with the prongs in the nails the bar 19 is drawn upwardly whereby the parts are actuated 60 to the positions shown in Fig. 3 whereby nails are gripped by the prongs.

The parts are held in this position by holding the rod 19 upwardly and the prongs 17 and 18 inwardly until 65 the tool is positioned over a tray of scales or over a bag or container, at which time the bar 19 is released and the springs draw the bar 19 downwardly to the position shown in Fig. 1 in which position the prongs are spaced, as shown in Fig. 2 so that nails or the like are dropped from the tool.

70 It will be understood that modifications, within the scope of the appended claims, may be made in the design

and arrangement of the parts without departing from the spirit of the invention.

What is claimed is:

1. A nail gripping tool comprising an inverted U-shaped frame forming a handle having vertically disposed arms at the ends with cross bars at the lower ends of the arms, bars pivotally mounted in the ends of the cross bars and positioned between the arms of the handle, spaced prongs carried by the bars and extended downwardly therefrom, a rod slidably mounted in the arms of the handle, means for actuating the bars carrying the prongs by the rod slidably mounted in the handle, resilient means for actuating the rod slidably mounted in the handle for turning the bars pivotally mounted in the cross bars to actuate the prongs to release objects held thereby, and a plate secured to the undersurface of the crossbars intermediate of said prongs.

2. In a gripping tool, the combination which comprises an inverted U-shaped handle having vertically disposed arms with cross bars on the lower ends at the ends of a connecting bar, bars with inwardly extended arms positioned between the arms of the handle, means pivotally mounting said bars in the cross bars, spaced prongs extended downwardly from the pivotally mounted bars, a rod slidably mounted in the arms of the handle, links 25

15

20

carried by the rod and pivotally connected to the arms extended inwardly from the bars pivotally mounted in the cross bars, springs connecting the rod to the pivotally mounted bars, and a plate secured to the undersurface of the crossbars intermediate of said prongs.

3. In a gripping tool, the combination which comprises an inverted U-shaped handle having vertically disposed arms with cross bars on the lower ends at the ends of a connecting bar, bars with inwardly extended arms positioned between the arms of the handle, means pivotally mounting said bars in the cross bars, spaced prongs extended downwardly from the pivotally mounted bars, a rod slidably mounted in the arms of the handle, links 10

15

20

carried by the rod and pivotally connected to the arms extended inwardly from the bars pivotally mounted in the cross bars, springs connecting the rod to the pivotally mounted bars, and a plate providing a shield positioned between the prongs.
